UNITED STATES PATENT OFFICE

2,532,649

BLEACHER STRUCTURE

James W. Thompson, Alexandria, La.

Application November 23, 1948, Serial No. 61,594

1 Claim. (Cl. 29—1.126)

1

This invention relates to new and useful improvements and structural refinements in bleachers, and the principal object of the invention is to provide a bleacher structure of the character herein described, which is of a discriptible nature so that it may be conveniently and readily transported from one location to another and so that it may be easily stored when it is not in use.

One of the features of the invention resides in what may be referred to as a "pre-fabricated" arrangement of the bleacher structure, whereby erection and dismantling thereof is greatly facilitated.

Some of the advantages of the invention lie in its simplicity of construction, in its pleasing appearance, in its rigidity and durability, and in its adaptability to economical manufacture.

With the above more important objects and features in view, and such other objects and features as may become apparent as this specification proceeds, the invention consists essentially of the arrangement and construction of parts as illustrated in the accompanying drawings, in which:

Figure 1 is a side elevational view of the invention;

Figure 2 is a fragmentary rear elevational view thereof;

Figure 3 is a fragmentary perspective detail illustrating the support means for the seat and foot rest providing boards;

Figure 4 is a fragmentary perspective view showing the attachment of a leg extension to a support leg used in the invention;

Figure 5 is a fragmentary cross-sectional view, taken substantially in the plane of the line 5—5 in Figure 4;

Figure 6 is a fragmentary cross-sectional detail, taken substantially in the plane of the line 6—6 in Figure 3;

Figure 7 is a fragmentary side elevational view, similar to that shown in Figure 1, but illustrating a modified embodiment of the invention.

Like characters of reference are employed to designate like parts in the specification and throughout the several views.

Referring now to the accompanying drawings in detail, the invention consists of a bleacher structure designated generally by the reference character 10, the same consisting of a plurality of spaced supports 12 carrying sets of seat and foot rest forming boards or planks 14, as will be hereinafter described.

The supports 12 are similar in construction, so that a description of one will suffice for all.

Each of the supports 12 consists of an inclined truss 16 provided at the elevated end portion thereof with a downwardly extending leg 18, this truss, including the leg portion thereof, being

best shown in Figure 1, wherein it will be apparent that the truss, including the leg portion, consists of a plurality of suitable structural members which are rigidly secured together by welding, or the like.

The truss 16 and the leg 18 are, of course, suitably reinforced as exemplified at 20, 22, 24, etc. and it is to be noted that the lower end 26 of the truss rests upon the ground indicated at 28.

A vertical leg extension 30, similar in construction to the truss 16, is provided at the lower end of the truss leg 18, this being effected by equipping the lower end of the leg 18 in the upper end of the extension 30 with a pair of support plates 32, 34, respectively, which plates may be separably secured together by suitable fastening elements, such as for example, the bolts 36, as is best shown in Figures 4 and 5.

The lower end of the leg extension 30 is, in turn, provided with a suitable foot member 38 resting upon the ground.

Sets of spaced parallel rods 40 are secured, preferably by welding, at their longitudinally spaced points to the upper, inclined edge of the truss 16, these rods or bars being angulated to extend horizontally and vertically from their points of attachment to the truss, so as to provide what may be referred to as sets of spaced parallel supporting members designated by the separate reference character 42.

The sets of supporting members 42, are, of course, horizontally disposed and are adapted to receive thereon aforementioned sets of horizontal boards or planks 14, the latter constituting alternate seats and foot rests of the bleacher structure, as will be clearly apparent.

The several supports 12 are erected in spaced relation and are connected together by suitable tie rods 44, 46 attached to the truss legs 18 and leg extensions 30, respectively (see Figure 2) and if desired, transverse reinforcing beams or straps 48 may also be employed for securing together the legs 18 of the several supports immediately adjacent the leg plates 32.

The boards or planks 14 are positioned on the supporting members 42 provided on the erected supports 12, and suitable fastening elements such as bolts 50, equipped with washers 52 and nuts 54, extend through the planks 14 and pass between the support members 42, whereby the planks are firmly and securely attached to the support members and hence, to the supports themselves. This arrangement is best illustrated in the accompanying Figures 3 and 6, and it will be noted that three of the support members 42 are provided in each set, so that ends of the planks may be placed in abutment and carried by the support members, substantially as shown. However, where intermediate portions of the planks are supported, only two of the support

members may be provided in a set, with the fastening elements 59 passing therebetween. That is to say, only two support members may be used in a set at the ends of the bleacher structure, and a set of two support members may also be employed intermediate the ends of the planks in instances where the planks extend between or span the distance between three or more supports.

If desired, the supports at the ends of the bleacher structure may be provided with upstanding members 56 carrying an inclined hand rail 58, and a back rest or rail 60 may be provided on vertical extensions 62 with which the elevated end portions of the supports 12 may be equipped, substantially as shown in Figures 1 and 2.

In the modified embodiment of the invention illustrated in the accompanying Figure 7, the truss 70 similar to the aforementioned truss 16, is equipped at the lower end thereof with a vertical extension 72, while the extension of the truss leg at the elevated end of the truss (not shown) is correspondingly increased in height, whereby the entire bleacher structure is supported at a higher level rather than having its lower or front portion resting directly upon the ground.

In the embodiment shown in Figure 7, the extension 72 may be equipped at its lower end with a ground engaging member 74 similar to the aforementioned member 38, while the upper end of the extension is equipped with a bolting plate 76 secured as at 78 to a further bolting plate 80 provided at the lower end portion of the truss. The remaining portion of the bleacher structure shown in Figure 7 is substantially similar to that already described in connection with the embodiment 10.

It is believed that the advantages and use of 40

the invention will be clearly understood from the foregoing disclosure and accordingly, further description thereof at this point is deemed unnecessary.

5 While in the foregoing there has been shown and described preferred embodiments of this invention it is to be understood that minor changes in the details of construction, combination and arrangement of parts may be resorted to without departing from the spirit and scope of the invention as claimed.

Having described the invention, what is claimed as new is:

In a bleacher structure, the combination of an inclined stringer, a set of three spaced parallel rods affording stepped horizontal supports and secured at longitudinally spaced points to the upper edge of said stringer, a set of tread forming boards extending transversely of said supports and having abutting end edges disposed above the axis of the center rod in the set, and fastening elements provided in the abutting end portions of said boards and extending through the spaces between said rods, whereby the boards are adjustably and removably secured to said supports.

JAMES W. THOMPSON.
